UNITED STATES PATENT OFFICE.

KARL BJÖRKSTEN, OF PETROGRAD, RUSSIA.

TYPE-WRITER.

1,215,102.

Specification of Letters Patent.

Patented Feb. 6, 1917.

Application filed July 6, 1915. Serial No. 38,264.

To all whom it may concern:

Be it known that I, KARL BJÖRKSTEN, a subject of the Emperor of Russia, residing at Fontanka 47, Petrograd, Russia, have invented certain new and useful Improvements in Type-Writers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Typewriters of the Hammond type have a very serious drawback which hinders them from being extensively used in offices and generally where writing is done on sheets of legal cap size or on heavy paper or where manifolding is required.

20 This drawback is due to the fact that when such paper is used the sheets become folded or creased, giving to the work a slovenly appearance, and use of a large number of sheets in manifolding is quite impracticable. The reason for this is that on placing the paper in the machine the sheet is first stored in a cylindrical receiver of a comparatively small diameter.

25 The object of my invention is to overcome this disadvantage in machines of the Hammond type by eliminating the cylindrical receiver and the invention consists in providing a special construction of hammer which will permit the insertion of the sheets between the guide and feed rollers from the rear of the machine, which is not possible with the form of hammer now in use.

In the accompanying drawings—

30 Figures 1 and 2 show a cross section and rear view, respectively, of a portion of a Hammond typewriter of known pattern.

Figs. 3 and 4 are similar views showing one form of hammer embodying my invention.

35 Figs. 5 to 7 illustrate a modification; Fig. 5 being a rear view, Fig. 6 a plan view, and Fig. 7 a section on line A—B of Fig. 5.

As shown in Figs. 1 and 2 the sheet 1 is fed 40 by the two feed rollers 2 and 3 of the longitudinally movable carriage from the cylindrical receiver 4, in which it may assume the form indicated. The sheet is prevented from taking another direction by the whole 45 construction and arrangement of the machine and especially that of the hammer 5

which is formed with a small head for engaging the paper and rocks on the axle 6 at the rear of the machine.

On each depression of a key the feed rollers are actuated by the spacing mechanism, and the hammer which rocks in one vertical plane strikes against the sheet whereby the latter is pressed against the anvil 7, the shuttle or type-wheel 8 of which, moves in such a manner that the proper type is brought opposite the striking face of the hammer as is well known in machines of this type.

According to the embodiment of the invention shown in Figs. 3 and 4 the arm of the hammer 5 is formed with a transverse slotted portion 9 through which the sheet is passed from the rear of the machine and which is of sufficient length to permit the sheet to be moved laterally with the longitudinally movable feed rollers past the anvil and hammer in the usual manner.

The same result is attained by the modified construction shown in Figs. 5 to 7, 30 wherein the hammer 5 is mounted on a frame 12, of the form shown, which is centrally fixed on the actuating axle 6 and supported at both ends by rock arms 13. The pivots 14 of these arms have their axes coinciding with the axis of axle 6.

The arms 13 rest on springs 15 (Fig. 7) and operate to prevent the frame from bending or twisting during the movement of the hammer and insures a correct impact of the latter.

It will be clear that by constructing the hammer as herein shown and described, the sheet may be inserted in the machine so as to avoid the cylinder, and readily and accurately fed through the machine and thereby eliminate a very objectionable feature without interfering in any way with the general construction of the machine.

My improved form of hammer may readily be substituted for the old form now in use without altering other parts of the present machines. The storage cylinder may, of course, be dispensed with and the space occupied by it utilized for other purposes.

I claim—

1. In a typewriter, the combination with a type-wheel rotatable on a fixed axis, and mechanism for laterally and longitudinally feeding a sheet past said wheel, of a hammer frame, a small head centrally mounted thereon and movable thereby in a fixed ver-

tical plane to and from the wheel, said frame having a transverse slotted portion adapted to permit longitudinal and lateral movement of the sheet therein.

- 5 2. In a typewriter, the combination with a type-wheel rotatable on a fixed axis, and mechanism for laterally and longitudinally feeding a sheet past the periphery of said wheel, of a hammer frame pivoted behind the latter, a small head centrally mounted on the frame and movable thereby in a fixed vertical plane to and from the wheel, said frame having a transverse slotted portion
- 10

adapted to permit longitudinal and lateral movement of the sheet therein, a central 15 lever supporting the frame, lateral supporting arms on said frame pivoted on axes coinciding with the axis of the lever, and springs to yieldingly support said arms.

In testimony that I claim the foregoing 20 as my invention, I have signed my name in presence of two subscribing witnesses.

KARL BJÖRKSTEN.
